UNITED STATES PATENT OFFICE

WILLIAM H. BAKER, OF CENTRAL FALLS, RHODE ISLAND, AND FREDERIC E. KIP, OF MONTCLAIR, NEW JERSEY.

LOOM.

SPECIFICATION forming part of Letters Patent No. 633,945, dated September 26, 1899.

Application filed March 29, 1899. Serial No. 711,026. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented certain new and useful Improvements in Looms, of which the following is a specification.

This invention relates to that class of devices employed for automatically supplying filling or weft to a loom; and it has for its object partly to employ electricity for controlling and determining the supply of filled shuttles to a loom and partly to provide simple and efficient mechanical means for carrying out the invention, all as will be more particularly hereinafter described.

In the accompanying drawings, which illustrate an embodiment of the invention, Figure 1 is a vertical sectional view of a part of a loom, illustrating the invention, the section being substantially in line α in Fig. 2. Fig. 1^a is a view similar to Fig. 1, but showing the parts in a different position. Fig. 2 is a plan of the parts of the loom seen in Fig. 1. Fig. 3 is an end view of the loom on a smaller scale than the principal figures and designed to illustrate the spring-arm carrying the shuttle-box and the relative position of the picker mechanism thereto. Fig. 4 is a plan of the parts seen in Fig. 3, and Fig. 5 is a view seen from the right in Fig. 3. Figs. 6 and 7 are enlarged views of the shuttle and bobbin with electrical connections, the former being a sectional side view and the latter a plan. Fig. 8 is a side view of the shuttle-box, showing the electrical connections with the shuttle.

1 is the breast-beam of a loom; 2, the lay head or beam. 3 are the uprights carrying the lay-head 4. 4 is the swing-rail or rock-shaft on or about which the lay swings in its ordinary reciprocating movements in beating up, and 5 is the reed carried by the lay. 6 is the picker-stick, which may be operated by the usual means. These parts are all common in looms and are constructed in a general way the same in most, if not all, power looms. This invention is not restricted to any special construction of these parts.

50 The purpose of the invention is to provide a

means, controlled electrically, whereby when the thread on the bobbin in the shuttle in the loom is exhausted or nearly exhausted the shuttle will be dropped from the shuttle-box on the lay and a filled shuttle supplied from a shuttle-magazine. The denudation of the bobbin in the shuttle serves to close an electric circuit, and this circuit controls the shifting of the shuttles. The mechanism for effecting this purpose will now be described.

60 7 is the shuttle-magazine, in which the shuttles 8 are superposed. This magazine is just large enough to accommodate the shuttles, and it is or may be supported on a bracket 9 on the breast-beam 1.

65 10 is a movable portion of the shuttle-box, comprising a bottom and one side, and 10^a is the other side of said box, mounted on the lay-head 2. The movable portion or section 10 of the shuttle-box is mounted on the upper 70 end of a spring-arm 11, pivotally mounted at its foot, Figs. 3 and 5, on the swing-rail 4, and a spring 12, fixed at its lower end on one of the uprights 3, supporting the lay-head, bears at its upper end on the back of the arm 75

11. This spring keeps the section 10 of the shuttle-box pressed normally up into the position seen in Fig. 1. The drawings show the lay in its terminal position when "beating up." Normally a slide 13, backed by suitable 80 springs 14 or the like and mounted in a guide-way in the bracket 9, projects under the magazine 7 and prevents the shuttles 8 from falling down and out; but if the spring-arm 11 be pressed or pushed over toward the breast-beam to the position seen in Fig. 1^a the section 10 will engage a lug 13^a on the slide 13 and press the latter back, thus allowing a shuttle 8 to drop into said shuttle-box section 10. The shuttle already in the shuttle-box 90 when this movement takes place will drop down to the floor or into a suitable receptacle, as it will be held against following the section 10 by a spring-detent 15, attached to the fixed portion of the shuttle-box and extending over 95 and across the shuttle. The outward movement of the box-section 10 draws the bottom of the shuttle-box from under the shuttle therein, and the lay-head is cut away so as to allow the shuttle to fall out freely.

The movement of the spring-arm 11 is effected by a lever 16, (see Figs. 1, 1^a, 2, 3, and 4,) fulcrumed at y on the lay-head 2 and its longer arm so situated as to bear on the back 5 of the spring-arm. Indeed, it will be loosely coupled to said arm by preference. The other or shorter arm of the lever 16 has on it a nose 16^x, which as the lay beats up plays under the elevated end of an armature-lever 17, fulcrumed at z on the breast-beam, Figs. 1 and 1^a, and carrying an armature m adjacent to the poles of an electromagnet M , carried by a bracket 18 on the breast-beam. When this magnet is excited and draws down the armature and its lever against the supporting-spring 19 of said lever 17, it will put the end of said lever in the path of the nose 16^x on the lever 16, and at the next beating-up movement of the lay 2 this nose 16^x will impinge 20 upon the end of the armature-lever 17, and as the lay continues to move forward the movement of the shorter arm of the lever 16 will be arrested; but the fulcrum y will continue to move forward, thus causing the longer 25 arm of the lever to press forward the spring-arm 11, and this latter will carry the section 10 of the shuttle-box to the position seen in Fig. 1^a. When the lay-head 2 swings outward again, the section 10 of the shuttle-box 30 will close in, carrying the shuttle with it to the position seen in Fig. 1, the slide 13 again closing the bottom of the magazine.

The electrical controlling devices whereby the electromagnet M is excited when the bobbin or cop in the shuttle in the loom shall have been denuded or nearly denuded of weft or filling will now be described with especial reference to Figs. 6, 7, and 8.

The shuttle 8 in the form herein shown 40 contains a spindle 20, hinged at its larger end in the shuttle in a known way, and on this spindle is slipped a cop or butt-cop. Cops and butt-cops are well known; but the butt-cop 21 herein shown is specially constructed 45 in some respects for effecting circuit connections or closures, and these features will now be described. On the spindle 20 is a loose metal ring or conical annulus 22, backed by a spring 23, and fixed on the spindle is a stop-collar 24 to limit the movement of said ring 22 when the spindle is empty. This ring 22 is connected electrically by a conductor 25, Fig. 7, with a piece or plate of metal 26, set in the outer face of the shuttle at its side. 50 The butt-cop 21, carrying the weft, is slipped onto the spindle, as seen in Figs. 6 and 7. It has on its larger part a metal ring 28, connected by a metal strip or wire 29 with a metal ferrule 30 on the smaller part of the cop. It 55 has also set in its end a piece or ring 31, of metal, which is pressed into contact with the conical annulus 22 on the spindle. The piece 31 is insulated from the ring 28 and has attached to it a metal spring 32, which plays in 60 a slot in the cop, and its free end takes under or within the ferrule 30 thereon at the

slot. A part 32^x of the spring 32 projects out from the slot in the butt-cop, and this exposed portion is overwrapped by the weft-thread in winding the cop, so as to put the 70 contact-spring 32 under a slight tension and keep its free end pressed away from the inner face of the ferrule 30. In Fig. 6 a little of the weft v is shown as wrapped over the spring 32 at 32^x and holding said spring 75 pressed in. The ring or band 28 is adapted to form an electrical contact with a piece or rod of metal 33 in the shuttle when the hinged spindle bearing the cop is pressed down into the shuttle. As here shown, there is a circumferential groove in the ring or band 28, and this is engaged by the piece 33, which is in the form of a cross-rod or stiff wire. The contact-piece 33 is electrically connected by a conductor 34 in the shuttle with a piece or plate of metal 26^x, set in the outer face of the shuttle at its side and forming with the piece or plate 26 what may be called the circuit-terminals of the shuttle. In Fig. 6, owing to the nature of the figure, the conductors 25 and 90 34 are represented diagrammatically. The conductor 25 may be conveniently formed integrally with the spring 23.

By following the construction above described it will be seen that the plate 26 is connected electrically with the spring 32 through the conductor 25, spring 23, sliding annulus 22, and ring or piece 31, and that the plate 26^x is connected electrically with the ferrule 30 through the conductor 34, the contact rod or piece 33, the ring or band 28, and the conductor 29. Thus if the free end of the spring 32 is allowed to come into contact with the ferrule 30 by the denudation of the cop the electric circuit will be completed between the 105 plates 26 and 26^x.

Referring now to Fig. 8 particularly, which shows the shuttle driven into the shuttle-box by the picker, it will be seen that in the side 10^x of the shuttle-box are two apertures 35 and 35^x, which are found opposite to the respective plates 26 and 26^x on the shuttle in the box, and on the box-side 10^x, adjacent to these apertures, are mounted contact-terminal springs 36 and 36^x, which bear on the respective plates 26 and 26^x of the shuttle. These contact-springs form terminals of an electric circuit w , including any suitable generator G and the coils of the electromagnet M . The weft or filling on the cop or 110 bobbin will, as before stated, break the electric circuit, or hold it open, between the ferrule 30 and spring 32 until the weft is wholly or nearly exhausted, only a little of it remaining on the butt-cop back of the point 32^x. 125 When the cop is thus denuded, the spring 32 will spring outward and close the break between it and the ferrule. When this is the case and the shuttle is driven into its box, the circuit will be completed at the plates 26 and 26^x and the magnet M excited. This will 130 place the armature-lever 17 in the path of

the nose 16^x on the lever 16, and at the next beating-up movement of the lay the exhausted shuttle will be discharged and a filled one taken in from the magazine, as before explained.

Referring now to Fig. 1, it will be noted that a part of one side or face of the magazine 7 is hinged like a door and held closed by a spring. This is to hold back the upper shuttles 8 and allow the lower one to fall out freely. 7^x is a part or section of one side of the magazine, hinged to the fixed part at its upper edge and held up in place by a spring 7^a. The lower portion of this hinged section is 15 cut away on the inner face at 7^b to allow easement or looseness of the lower shuttle. When the slide 13 moves in to the position seen in Fig. 1, its end strikes and pushes out the lower end of the section 7^x of the magazine a very 20 little, thus allowing the shuttles in the magazine to settle down by gravity; but when the moving section 10 of the shuttle-box drives back the slide 13 the spring 7^a causes the upper part of the section 7^x to press firmly upon 25 and clamp the shuttle next above the bottom one and hold it and those above it from descending, thus leaving the bottom shuttle free to fall into the shuttle-box section 10.

Figs. 3 and 4 do not show the shuttle-magazine 7. They are designed, mainly, to illustrate the form of the parts 3, 11, and 12 and the construction of the parts at the bottom of the loom.

The ends of the weft-threads from the bobbins in the shuttle are led out through a vertical slot 7^c in the side of the magazine 7 and attached at *u* or at some other convenient point. Any means of attaching the threads may, however, be employed.

It will be understood that while we have described our invention as it is herein illustrated we do not limit ourselves to the exact construction shown, as this may be varied to a considerable extent without departing from our invention. For example, the spring 12 is only one form of spring that might be employed for this purpose. There are also other known devices for holding up the shuttles in the magazine, and we do not limit ourselves 45 to the means herein shown. Different styles of looms, also, will require some modification in the construction of the supply device, and the different forms of weft-holders in the shuttles, such as bobbins, cops, &c., will make 50 some modification in the electrical devices necessary.

The specific features of the invention are the sectional shuttle-box, the movable section being adapted to move under the magazine, receive a shuttle, and carry it to the lay, and the electrical devices controlling this movement through the denudation or partial denudation of the bobbin or cop.

By the words "denuded," "denudation," 60 and "exhausted" as applied to the weft-holder and weft is not meant, necessarily, the actual absence of all the weft or filling

from the holder, but such degree of denudation as will permit the automatic devices in the shuttle to close the circuit.

Being the first, as we believe, to employ electrical means for controlling the weft-supply of a loom in a mechanism for automatically supplying the weft or filling to the loom, we do not limit ourselves to specific means for 75 this purpose, as such means may be varied almost indefinitely.

We have not shown in the figures all of the various parts of the loom, but enough are shown to illustrate the present invention. 80

Having thus described our invention, we claim—

1. Weft-supply mechanism for a loom comprising a shuttle-magazine, a sectional shuttle-box, the movable section of which reciprocates from its normal position on the lay-head to a position to receive a shuttle from said magazine, an electric circuit and mechanism controlling said reciprocating movement of the shuttle-box section, and means carried 85 by the shuttle for closing and completing said circuit when the supply of weft in the shuttle is exhausted.

2. The combination with a shuttle-magazine, the lay, the non-moving section of the 95 shuttle-box carried by the lay, the reciprocating section of the shuttle-box mounted on a spring-arm which vibrates with the lay, a lever carried by the lay and adapted to operate said spring-arm, an electric circuit and 100 electrical mechanism therein, controlling the operations of said lever, and means carried by the shuttle for completing the circuit through said electrical mechanism when the weft is exhausted from the weft-carrier in the 105 shuttle.

3. The combination with the lay, and the fixed shuttle-magazine, of a slide which closes the bottom of said magazine automatically, the shuttle-box, having a movable section 110 adapted to operate said slide, mechanism for moving said section of the shuttle-box, an electric circuit and mechanism controlling said mechanism which operates the shuttle-box section, and means carried by the shuttle 115 for completing the circuit through said controlling mechanism when the weft is exhausted from the weft-carrier in the shuttle.

4. The combination with the vibrating lay, the fixed shuttle-magazine, and the movable 120 section of the shuttle-box, of the lever 16, carried by the lay, one arm of said lever being adapted for operating said shuttle-box section, and the other provided with a nose 16^x, of the magnet M, fixed with respect to 125 the lay, the armature *m* of said magnet, the lever 17 carrying said armature and normally out of the path of the nose 16^x, the controlling electric circuit including said electromagnet and a generator, and a partial circuit 130 in the shuttle adapted to be closed by the denudation of the weft-thread in the shuttle, said partial circuit having contact-terminals which are put in contact with terminals of

the controlling-circuit when the shuttle enters its box, substantially as set forth.

5. In a mechanism for the purpose described, the combination with the movable section 10, of the shuttle-box, means for moving said section, the lay 2, cut away to allow the shuttle to fall from the box, and the stationary part, 10^x, of said box, of the detent 15, which prevents the shuttle from being carried out by 10 the box-section 10, substantially as set forth.

6. Weft-supply mechanism for looms, comprising a shuttle-magazine, a shuttle-box on the lay, having a movable section which reciprocates from its normal position to a position to receive a shuttle from said magazine, thus opening the box for the discharge of the exhausted shuttle, means for operating said section of the box, an electric circuit controlling said operative means, said circuit including a generator and having terminals at the shuttle-box, and the shuttles, each having in it an electric circuit with terminals which contact with those on the shuttle-box when the shuttle is in place therein, said circuit in the shuttle having in it a break which 25 is closed by the denudation of the weft-holder in the shuttle.

7. In an electrically-controlled weft-supply mechanism for looms, a weft-holder for insertion in the shuttle, carrying a metallic contact part forming part of the circuit controlling said supply mechanism, another, spring-like contact part, also forming part of said controlling-circuit and adapted to automatically form contact with the first-named contact part, but held normally out of contact therewith by the overwrapping of the weft-thread about the holder, substantially as set forth.

40 8. In an electrically-controlled weft-supply mechanism for looms, the combination with a shuttle-box on the loom, said box having on it terminals of the main, outer operating-circuit, and a shuttle having on it contact-plates 45 which form terminals of that portion of the operating-circuit within the shuttle, of a weft-holder within said shuttle and provided with a hollow overwrapped by the weft-thread thereon, and normally-separated metallic contacts in said hollow and forming parts of said circuit, said contacts being held apart, so as to break the circuit, by said overwrapped thread, substantially as set forth.

9. As a new article of manufacture, a weft-holder for use in a shuttle, having in it a hollow and in said hollow metallic parts constituting conductors of an electric circuit, said conductors being held out of contact with

each other by the overwrapped weft-thread on the holder.

10. In a weft-supply mechanism for looms, the combination with a mechanical supply device, controlled electrically, of a partial outer electric circuit, including a generator and operating-magnet, and having terminals at the shuttle-box, the shuttle, a partial circuit in said shuttle, adapted to be closed, by the entry of the shuttle into the shuttle-box, with the said partial outer circuit, a weft-holder, and a partial circuit in a hollow in said weft-holder, adapted to be closed, when the holder is in the shuttle, with the partial circuit in the latter, said partial circuit in the weft-holder having in it a break which is held open by the overwrapped weft on the holder, substantially as set forth.

11. As a new article of manufacture, a shuttle for a loom containing a partial electric circuit, and having an automatic circuit-closer situated wholly within the shuttle, said circuit-closer having its two terminals situated within the mass of weft, and held open by the whirls of the weft-thread on one of its elements, the partial circuit of the shuttle having terminals on the exterior surface of the same, which are adapted to contact with circuit-terminals on the shuttle-box.

12. In a weft-supplying mechanism for looms, the combination with a mechanism for supplying the weft-holders to the loom, of the said holder, having an automatic closer for an electric controlling-circuit situated inside of the weft wound on the holder, said circuit being held open, normally, by the weft wound on the holder, whereby the operating-circuit is closed when the pressure of the weft is removed to a sufficient extent from said closer.

13. In a weft-supplying mechanism for looms, the combination with a mechanism for supplying the shuttles to the loom, of the said shuttles, each having an automatic circuit-closer situated wholly within the shuttle, said circuit-closer being held open by the whirls of the weft-thread on one of its elements, the partial circuit in the shuttle having terminals on the external surface of the same which are adapted to contact with terminals of the exterior circuit on the shuttle-box.

In witness whereof we have hereunto signed our names, this 16th day of March, 1899, in the presence of two subscribing witnesses.

WILLIAM H. BAKER.
FREDERIC E. KIP.
